UNITED STATES PATENT OFFICE.

OSCAR L. BILLINGS, OF PHILADELPHIA, PENNSYLVANIA.

DESIGN FOR A DIAL.

SPECIFICATION forming part of Design No. 22,054, dated December 6, 1892.

Application filed October 18, 1892. Serial No. 449,290. Term of patent 3½ years.

To all whom it may concern:

Be it known that I, OSCAR L. BILLINGS, a citizen of the United States, and a resident of Philadelphia, Pennsylvania, have invented a new and original Design for a Dial for Automatic Heat-Regulators, of which the following is a specification.

My design for a dial of an automatic damper-regulator is fully illustrated in the accompanying drawing, in which the view is a face view of the dial.

The essential feature of the design is the circular central section having a semicircular portion depending from it.

The central section of the dial is formed of a series of raised concentric ribs, and between the two outer ribs is a series of projections.

A semicircular portion depends from one-half of the central section and is bordered by a plain raised rib. Above each corner of the semicircular portion is scrollwork ornamentation, forming a finish between the said portion and the central section.

I claim—

The design for a dial, as herein described and shown.

In testimony whereof I have signed my name to this specification in the presence of two subscribing witnesses.

OSCAR L. BILLINGS.
